UNITED STATES PATENT OFFICE

WILLIAM F. BUTLER, OF HILLSIDE, NEW JERSEY, ASSIGNOR TO AMERICAN CAN COMPANY, OF NEW YORK, N. Y., A CORPORATION OF NEW JERSEY

METHOD OF AND MACHINE FOR LINING CAN ENDS

Application filed March 23, 1925. Serial No. 17,527.

My invention relates to can end flange lining machines and particularly to an improvement upon the machine disclosed in Patent No. 1,634,500, granted July 5, 1927, on application of John M. Hothersall, for machine for lining the flanges of can ends.

The principal object of the invention is the provision, in a machine of this character, of a lining head, or die, having a pump action and being adapted to project a measured charge of lining material forcibly onto the flange in such manner as to properly apply and distribute it to the flange area to be lined.

Numerous other objects and advantages of the invention will be apparent as it is better understood from the following description, which, taken in connection with the accompanying drawings, discloses a preferred embodiment thereof.

Referring to the drawings,

Figure 1 is a longitudinal sectional view of a lining machine in which my invention is embodied, the cover being held in position to be lined and the lining die being shown in its down position in the tank of lining material;

Fig. 2 is an enlarged cross sectional view of the lining die;

Fig. 3 is a partial sectional view thereof, showing the position of the parts at the time of contact with the can end and just prior to the charge being squirted onto the flange;

Fig. 4 is a like view, showing the relation of the parts after the charge has been applied; and

Fig. 5 is a top plan view of the lining ring or die.

On said drawings, illustrating the best manner in which I have thus far contemplated applying the principles of my invention, the reference character 11 indicates a table, supported upon legs 12 and 13, the latter having an inward extension 14, providing bearings for a shaft 15, which may be a power shaft, driven from any suitable source of power and a rock shaft 16, upon which is mounted a bell crank lever 17, connected for actuation of the lining die in manner which will presently be described. A tank 18 is formed integrally with the table 11, near the

center thereof, and the covers are adapted to be fed along a track 19 upon said table by means of a feed bar 21, provided at intervals with pivoted fingers 22 adapted to engage behind and propel the covers successively to the lining station and to discharge them from the machine. Said bar is formed with teeth 23 on the top thereof at one end, providing a rack meshing with a pinion 24, carried upon a shaft 25 adapted to be rotated in opposite directions, in any suitable or preferred manner, proper mechanism for this purpose being shown in the Hothersall pending application above referred to. Said bar 21 moves in a guideway formed in a top plate 26, said plate being formed to receive a plurality of electromagnets 27 above the lining station, which magnets serve to hold said covers firmly in contact with the under side 28 of said plate when at said lining station.

The bell crank 17 carries in one arm 29 thereof a cam following roller 31, held in contact with a cam 32 on the shaft 15 by means of a spring 33, secured at one end to said arm 29 and at the opposite end to a fixed part of the machine. The opposite arm of the bell crank, which is designated by the reference character 34, is pivotally connected by means of a link 35 with a rod 36 extending through a stuffing box 37 and into the tank 18, where it is connected with the lining die which is adapted to be reciprocated thereby, in manner which will now be described.

The lining die, or head, comprises an outer cylindrical member 38 and an inner member 39, which has a relatively tight friction fit with said outer member, said members being, however, relatively movable in the operation of the device. Said member 38 is formed with web parts 41 at the bottom thereof, extending from the outer wall to a central enlargement or hub 42, through which the rod 36 extends, the latter being frictionally held therein. The upper edge of the cylindrical member 38 is cut away to provide a pocket 46 for the lining charge, indicated in Fig. 3 by the reference character 47, and the inner member is provided with a shoulder 48 near the top and a wall part 49 thereabove of slightly less diameter than the di-

ameter of a wall part 51 about the pocket 46. Screw rods 52 extend downwardly from a plurality of lugs 53, extending inwardly from the bottom of the member 39, and pass through apertures 54 in the web parts 41 of the member 38. On the downward stroke of the head, said rods engage the bottom of the tank 18 and raise the member 39 to the position shown in Figs. 1 and 2 of the drawings.

10 When the head is immersed in the semi-liquid lining compound in said tank, the pocket 46 is filled with the lining material, which is carried upwardly thereby, as shown in Fig. 3, until the wall part 49 of the member 39 comes into contact with the flange of the can cover, which is indicated by the reference character 55. Inasmuch as said cover is firmly held in position, as previously described, said member 39 will then be held stationary and the outer ring 38 will be moved relatively thereto to the position shown in Fig. 4, the lining material being bumped or squirted out between the wall parts 49 and 51 and onto the flange of the end 55 to provide a liner 56, the size and distribution of which may be controlled in accordance with the form of the parts 38 and 39.

The amount of relative movement between the parts 38 and 39 can be varied by adjusting the position of the screw rods 52 within their respective lugs 53. Spring pins 45 are positioned between each screw rod 52 and a part of the inner wall of the member 39 adjacent thereto, and in this position are held under tension and bear against the said rods 52, preventing accidental turning but permitting adjustment.

A lever 57, pivoted at 58 to an upright 59 extending upwardly from the bottom of the tank 18, is provided for the purpose of preventing operation of the die when no cover is in position to be lined. Said lever has an upper arm or extension 61, normally held in the path of the ends by means of a coil spring 44 positioned about the pivot point 58, the bottom end of the lever being notched, as indicated at 62, and adapted to engage one of the webs 41 of the member 38. In the event that no cover is positioned, said lever prevents the lifting of the die, in manner which will be apparent, the bell crank 17, in this event, remaining also stationary, the cam roller 31 carried thereby being prevented from following the face of the cam 32, the spring 33 being held extended at such a time. If, however, a cover is positioned, it acts upon said lever to cause the same to disengage said web 41, permitting the lifting of the die and the operation thereof in the manner hereinbefore explained. The reference character 61' indicates a vent pipe, of which there may be one or more in the tank.

It is thought that the invention and many of its attendant advantages will be understood from the foregoing description, and it

will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A flange lining machine for can ends, comprising a tank for the lining material, means for arranging the ends at a lining station above said tank, and a lining head adapted to carry material upwardly from the tank and apply the same to the flange of a can end, said head comprising parts relatively movable on the up stroke of the head to squirt the lining material onto the end flange. 75

2. A flange lining machine for can ends, comprising a tank for the lining material, means for arranging the ends at a lining station above said tank, and a lining head adapted to carry material upwardly from the tank and apply the same to the flange of a can end, said head comprising an outer ring provided with a pocket for carrying the charge of lining material and an inner ring adapted to contact with the can end on the up stroke of the head and to cooperate with said outer ring to project the lining material from said pocket onto the end flange. 80

3. A flange lining machine for can ends, comprising a tank for the lining material, means for arranging the ends at a lining station above said tank, and a lining head adapted to carry material upwardly from the tank and apply the same to the flange of a can end, said head comprising an outer member formed at the upper edge thereof to carry a charge of the lining material and an inner member formed to discharge the said material upon relative movement of said members produced upon the up stroke of the head, the material thus discharged being directed onto the end flange. 95

4. A flange lining machine for can ends, comprising a tank for the lining material, means for arranging the ends at a lining station above said tank, and a lining head adapted to carry material upwardly from the tank and apply the same to the flange of a can end, said head comprising an outer member formed at the upper edge thereof to carry a charge of the lining material, an inner member formed to discharge the said material upon relative movement of said members produced upon the up stroke of the head, the material thus discharged being directed onto the end flange, and means for causing relative movement of said members on the down stroke to arrange them in starting position. 100

5. A flange lining machine for can ends, comprising a tank for the lining material, means for arranging the ends at a lining station above said tank, and a lining head adapted to carry material upwardly from the tank 115

and apply the same to the flange of a can end, said head comprising an outer member formed with a cut-out on the upper edge thereof and inwardly from the periphery and a member disposed within said outer member and having an outwardly extending wall part at the top thereof adapted to enter said cut-out upon relative movement of the outer member, said cut-out being adapted to carry a charge of lining material upwardly from the tank and the up movement of the inner member terminating before that of the outer member, whereby said charge of lining material is projected upwardly onto the flange.

6. A flange lining machine for can ends, comprising a tank for the lining material, means for arranging the ends at a lining station above said tank, and a lining head adapted to carry material upwardly from the tank and apply the same to the flange of a can end, said head comprising an outer member formed with a cut-out on the upper edge thereof and inwardly from the periphery, a member disposed within said outer member and having an outwardly extending wall part at the top thereof adapted to enter said cut-out upon relative movement of the outer member, said cut-out being adapted to carry a charge of lining material upwardly from the tank and the up movement of the inner member terminating before that of the outer member, whereby said charge of lining material is projected upwardly onto the flange, and means extending downwardly from said inner member and adapted to contact with the bottom of the tank on the down stroke of the head to restore said members to starting position.

7. A flange lining machine for can ends, comprising means for supporting the ends to be lined, a source of lining material, and yielding means operable by the pressure of the can end for carrying the compound from said source and thereafter applying it upward against the force of gravity with a squirting action simultaneously to all parts of the flange area to be lined.

8. A flange lining machine for can ends, comprising means for supporting the ends at a lining station, a tank for the lining material beneath said station, and yielding means operable by the pressure of the can end for carrying the lining material upwardly from said tank and thereafter applying it with a squirting action upward against the force of gravity to the flange area to be lined.

9. A method of lining can ends with fluid compound, which consists in carrying a segregated amount of the compound to a location in proximity to the part of the can end which is to be lined, and then pressing the can end against the compound carrying element and thereby forcibly squirting said located amount of compound into adhering contact with said part of the can end.

10. A method of lining can ends with fluid compound, which consists in carrying a segregated amount of the compound up from beneath the surface of a body of said compound to a location in close proximity to the part of the can end which is to be lined and underneath the same, and then pressing the can end against the compound-carrying element and thereby forcibly squirting said located amount of compound forcibly upward into adhering contact with the under side of said part of the can end.
